DESIGN FOR A REMOTE CONTROL APPARATUS CABINET FOR MUSICAL DEVICES

Edward E. Collison, Chicago, and Claude R. Kirk,
River Forest, Ill.

Application October 5, 1936, Serial No. 65,172

Term of patent 7 years

To all whom it may concern:

Be it known that we, Edward E. Collison and Claude R. Kirk, citizens of the United States, residing at Chicago, Cook County, Illinois, and River Forest, Cook county, Illinois, respectively, have invented a new, original, and ornamental Design for a Remote Control Apparatus Cabinet for Musical Devices, of which the following is a specification, reference being had to the accompanying drawing, forming part thereof.

In the drawing:

The figure is a perspective view of a remote control apparatus cabinet for musical devices showing our new design. Both side edges of the cabinet are similar and the back is plain.

We claim:

The ornamental design for a remote control apparatus cabinet for musical devices, as shown and described.

EDWARD E. COLLISON.
